UNITED STATES PATENT OFFICE.

CARL SCHUMACHER, OF NEWPORT, KENTUCKY.

AIR-BRAKE COUPLING.

NO. 836,344.

Specification of Letters Patent.

Patented Nov. 20, 1906.

Application filed June 11, 1906. Serial No. 321,215.

To all whom it may concern:

Be it known that I, CARL SCHUMACHER, a subject of the Emperor of Germany, residing at Newport, in the county of Campbell 5 and State of Kentucky, have invented a new and useful Air-Brake Coupling, of which the following is a specification.

This invention relates to couplings for air-brake systems.

10 In constructing an effective air-brake coupling by means of which the air-pipes of a train can be automatically connected and disconnected a number of difficulties are encountered. These difficulties are partly due to 15 the fact that the cars are not always constructed of the same size and proportions, for which reason the body portion of one car, and consequently the air-brake coupling thereof may be elevated to a greater degree 20 above the road-bed than the coupling of another car of different design. Furthermore, it frequently happens that a train is made up of some cars which are empty and others which are fully loaded, in which case the 25 loaded cars by reason of the compression of their springs have coupling members which are disposed lower to the ground than the coupling members of the empty cars. Furthermore, when the cars are old their coupling members frequently become worn and loose, so that they will not always coöperate 30 properly with the coupling members of new cars. Last, but not least, when automatic air-brake couplers are used it is generally 35 necessary that they be pressed positively together in the same manner as the ordinary car-couplers, for which reason when the car-coupler becomes worn and loose, as frequently happens, so as to permit play between the 40 cars, the delicate mechanism of the automatic coupling-valves soon becomes worn or destroyed.

The object of my present invention is to 45 overcome the difficulties above set forth and to provide a simple, inexpensive, durable, and thoroughly efficient automatic air-brake coupling.

With the foregoing and other objects in view, which will appear as the description 50 proceeds, the invention resides in the combination and arrangement of parts and in the details of construction hereinafter described and claimed, it being understood that changes in the precise embodiment of 55 invention herein disclosed may be made within the scope of the claims without departing

from the spirit of the invention or sacrificing any of its advantages.

In the accompanying drawings, forming a part of this specification, Figure 1 is a side 60 elevation showing one of the improved air-brake coupling members of this invention secured to the under side of an ordinary car-coupler. Fig. 2 is a front elevation of the air-brake coupling. Fig. 3 is a longitudinal 65 horizontal section showing two of the air-brake coupling members interlocked together. Fig. 4 is a rear elevation, partly in section, of one of the coupling members showing the slip-plate. Fig. 5 is a horizontal section 70 through the forward end or nose portion of one of the air-brake couplings, showing the automatic valve. Fig. 6 is a vertical section through the automatic valve, taken at a right angle to Fig. 5. 75

Like reference-numerals indicate corresponding parts in the different figures of the drawings.

In view of the fact that the coupling member on one car is exactly the same in form 80 and construction as the coupling member on the adjacent car it will be only necessary to describe one coupling in order to convey an understanding of both.

The reference-numeral 1 indicates a coupling member which is formed with a reduced tubular stem 2 and an internal bore or supply-passage 3. Projecting from what I shall term the "inner" side of the coupling member 1 is an approximately semicircular flange 4, which is formed with a flared entrance portion 5. The flared entrance portion 5 converges into an approximately semicircular socket 6, having its inner wall 7 inclined at an angle which is slightly more acute than 90 the angle of the entrance portion 5. The upper and lower walls of the socket 6 are inclined at the same angle as the inner wall 7. The outer wall 8, however, of the socket 6 is straight, as shown. The inner end of the 100 socket 6 is enlarged, as shown clearly in the drawings. In addition to the flange 4 the coupling member 1 is formed with a nose portion 9, the outer end of which projects beyond the flange 4 and is rounded slightly, as 105 shown at 10. At its semicircular outer end the nose 9 is formed with a rear wall 11, which is inclined at such an angle as to be parallel with the inner wall 7 of the socket 6. The upper and lower walls 12 at the outer 110 end of the nose 9 are similarly inclined, so that said nose will fit into the socket 6 of the

opposite coupling member except that the enlarged inner end of the socket 6 will form an open chamber around the rounded end of said nose 9, as shown in the drawings, where-
5 by any liability of blunting the nose when it is inserted into the socket is effectually avoided.

While the automatic valve mechanism by which communication is established between
10 the coupling members of cars when they are connected together and by which this communication is shut off when the cars are separated may be of any suitable form and construction, I prefer that this mechanism be
15 constructed as illustrated in the drawings, wherein the numeral 14 illustrates a plug which is threaded and screwed into the rear portion of a valve-chamber 15, formed in the outer end of the nose 9, and communicates in
20 any suitable manner with the passage 3.

One portion of the edge or corner of the plug 14 is beveled, preferably as indicated at
16, so as to form a continuation of the inclined wall 11 of the nose, and thus avoid
25 offering any outward obstruction. The threaded plug 14 preferably is formed with an annular chamber 17, which opens at its inner end into the valve-chamber 15. The valve proper comprises a body portion 18,
30 which is formed with an annular flange 19, extending back into the annular chamber 17 of the plug 14.

The flange 19 preferably is formed with an annular series of perforations 20. Arranged
35 inside the annular flange 19 is a coil-spring 21, which normally presses the valve inwardly, so that compressed air can pass from the valve-chamber 15 through the perforations 20 and into the annular chamber 17 of the plug 14. On its inner face the body portion 18 is formed with a cone-shaped projection 22, around which is fitted a cone-ring 23, which is secured in position by a cone-shaped steel head 24, having a threaded shank 24',
40 extending through the cone-shaped projection 22 and being locked against accidental rotation by means of a nut 26, located in the annular chamber 17.

When the coupling members of the two
50 cars are disengaged, the cone-shaped valve is pressed outward by the coil-spring 21 and rests against a cone-shaped valve-seat 28.

The annular chamber 17 of the plug 14 is always in communication with the valve-chamber 15 through the perforations 20 in the flange 19, so that the pressure on both sides of the valve will be equal and the valve will work smoothly.

When the two couplers are brought together, the two automatic valves contact with each other and open so as to permit communication between the two air-brake coupling members. Each cone-shaped valve preferably is guided in its movement by a plural-
65 ity of columns or valve-guides 29, which are

located in the valve-chamber 15 and are arranged at suitable intervals around the periphery of the valve.

The inner straight face 30 of the nose 9 preferably is provided with an annular packing-ring 31, which is suitably set into the face thereof and surrounds the valve-seat 28 at a slight distance therefrom.

It will be understood that when two cars are coupled together the nose 9 of each member slides along the flared entrance portion 5 of the opposite member and becomes seated in the socket 6, so as automatically to open the valves by causing the cone-shaped heads 24 to contact with each other. The semicircular flanges 4 cause the two coupling members to be accurately guided together even when one or the other of them has been displaced either in an upward, downward, or lateral direction.

It is one of the purposes of my invention to combine the air-brake coupling with the ordinary car-coupler, so that both sets of coupling members will be automatically locked at the same moment. Furthermore, it is a purpose of my invention to provide means for yieldingly pressing the air-brake coupling members together, so that they will not be injured by relative movement between the two cars caused by the looseness of the regular car-coupling, the yielding means which I employ for this purpose being also adapted to restore the air-brake coupler automatically to proper position to engage the coupler on another car whenever necessary. The preferred means for accomplishing the above result consists of a bracket 35, which is connected in any suitable manner with an ordinary car-coupler 35' and is provided with an annular depending vertically-disposed member 36, which is provided with a concavo-convex portion 37, constituting what I shall term a "slip-plate." The stem 2 of the coupling 1 extends loosely through the central opening in the slip-plate 37 and is provided with a nut 38, having a plurality of radially-extending arms 39, having curved ends 40 adapted to contact with the slip-plate 37 when the coupling is automatically held in advanced position, as hereinafter described.

The preferred means for holding the coupler in advanced position comprises a bell-crank lever 41, pivoted to the bracket 35, as indicated at 42, and having a short arm 43 and a relatively longer arm 44, provided with a counterbalance-weight 45. The short arm 43 of the bell-crank lever preferably is forked, so as to straddle a ring 46. Loosely secured to the coupling 1 are trunnions 47, which extend through perforations 48 in the ring 46, the perforations 8 being slightly larger than the trunnions 47, so as to permit relative movement of the coupling 1 inside the ring 46. The trunnions 48 of the ring 46 extend through perforations 49 in the forked por-

tions of the arm 43, the perforations 49 being larger than the trunnions 48, so as to permit relative movement.

From the foregoing description it will be apparent that a universal connection is provided between the lever 41 and the coupling member 1, so that said coupling member can move upward or downward or sidewise with respect to the lever. The rear end 44 of the lever 41 preferably is about twice the length of the short end 43 and is provided with a weight of about fifty pounds, which gives a forward pressure of about one hundred pounds on the ring 46, for which reason when said coupler is free—that is, when it is not connected with another coupler—the lever 41, forces it forward, so that the lateral arms 40 on the rear end of said coupler slip upon the plate 37 and accurately center the coupler with respect to the plate 37. In this way the coupler is automatically held approximately in its proper position, so as to be readily engaged with the coupler of another car, the proper engagement of said couplers being assured by reason of the fact that they are combined with the ordinary couplers of the cars. In the event that the ordinary couplers are worn, so as to permit relative movement between the two cars, the levers 41 yeldingly hold the two couplers together, so that the cars can move with respect to each other without loosening the air-brake coupling or injuring the same.

The improved coupler of this invention is strong, simple, durable, and inexpensive in construction, as well as thoroughly efficient in operation.

While the counterweight 45 under all circumstances will serve to hold the coupler yeldingly in advanced position, still, in view of the fact that upon irregular road-beds the vibration of the cars may be sufficient sometimes to cause the counterweight 45 to swing upward and downward sufficiently to interfere with the air-brake coupling, I prefer in some cases to employ a spring 60, which can be secured to the lower surface of the car-coupler 35' and extend downward into engagement with the arm 44. It will be understood that the spring 60, which constitutes means for holding the air-brake coupling yeldingly in advanced position, can be used in addition to the counterweight 45 or as a substitute therefor.

What is claimed is—

1. The combination with a car-coupler, of an air-brake coupling, and counterbalance means for holding said coupling in advanced position.
2. The combination with a car-coupler, of an air-brake coupling, an angle-lever connected with said coupling, and a counterbalance carried by said angle-lever.
3. The combination with a car-coupler, of an annular slip-plate, an air-brake coupling

extending through said slip-plate and having lateral arms adapted to engage said plate, an angle-lever connected with said air-brake coupling, and yielding means acting on said lever for holding said air-brake coupling in advanced position.

4. The combination of an air-brake coupling and counterbalance means for holding said coupling in advanced position.

5. The combination of an air-brake coupling, counterbalance means, and a universal connection between the coupling and counterbalance means.

6. The combination of a slip-plate, an air-brake coupling extending through said slip-plate and having arms to engage the same, a lever connected with said air-brake coupling, and yielding means acting on said lever for holding said coupling in advanced position.

7. The combination with a car-coupler, of an automatic air-brake coupling, an angle-lever having a counterbalance-weight, and a universal connection between the angle-lever and air-brake coupling.

8. The combination with a car-coupler, of a slip-plate, an air-brake coupling having a stem extending through said slip-plate and provided with lateral arms to engage said plate, an angle-lever fulcrumed above said slip-plate and having a counterbalance-weight connected therewith, and a universal connection between the angle-lever and the air-brake coupling.

9. An air-brake coupling having a flange formed with a flared entrance portion and a centrally-disposed socket, and a nose, the outer end of which is of approximately the same shape as the socket.

10. An air-brake coupling having a flange formed with a flared entrance portion and an approximately semicircular tapering socket communicating with the flared entrance portion, a nose having an approximately semicircular tapering outer end of approximately the same shape as the socket, and an automatic valve in said nose.

11. An air-brake coupling having a flange formed with a flared entrance portion, a nose having a valve-chamber therein formed with a valve-seat, a plug removably fitted into the outer end of the side of the nose and having an annular chamber therein, a valve comprising a body portion having an annular perforated flange extending into the annular chamber, and a cone-shaped projection extending from its outer face, a cone-ring fitting around said projection and a cone-shaped head having a shank extending through the body portion and provided with a nut located in said annular chamber, and a coil-spring in said annular chamber for forcing the valve outward.

12. An air-brake coupling comprising a coupling member having a flange formed with a flared entrance portion and a socket,

a nose, an automatic valve in said nose, a guide-plate surrounding the rear end of said coupling member, lateral arms connected with said coupling member and engaging said plate, and an angle-lever provided with counterbalance means and having a universal connection with said coupling member.

In testimony that I claim the foregoing as my own I have hereto affixed my signature in the presence of two witnesses.

CARL SCHUMACHER.
